CLAIM

The ornamental design for a bottle plate with cover ring, as shown and described.

DESCRIPTION

FIG. 1 is a top, right, front perspective view of a bottle plate with cover ring showing the new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is an exploded top, right, front perspective view thereof; and,

FIG. 9 is another top, right, front perspective view thereof, shown in a position of use with an exemplary support stand and bottle.

(Continued)

The broken lines are shown for the purpose of illustrating both parts of the article as well as environmental subject matter. None of the broken lines form part of the claimed design.

1 Claim, 6 Drawing Sheets
